UNITED STATES PATENT OFFICE.

ALEXANDER J. R. FIEGO, OF LYNN, MASSACHUSETTS, ASSIGNEE TO GENERAL ELECTRIC COMPANY, A CORPORATION OF NEW YORK.

MECHANICAL MOVEMENT.

1,157,933.

Specification of Letters Patent. Patented Oct. 26, 1915.

Application filed April 1, 1913. Serial No. 758,119.

To all whom it may concern:

Be it known that I, ALEXANDER J. R. FIEGO, a citizen of the United States, residing at Lynn, in the county of Essex, State of Massachusetts, have invented certain new and useful Improvements in Mechanical Movements, of which the following is a specification.

My invention relates to a mechanical movement.

10 The object of my invention is to provide a simple and substantially frictionless mechanical movement for transmitting the movement of one member to another member.

15 More particularly the object of my invention is to provide such a mechanical movement for transmitting the movement of a member arranged to turn through the arc of a circle to a second member also arranged to turn through the arc of a circle where the paths of movement of the members are in planes at substantially right angles to each other.

20 The novel features which I believe to be 25 patentably characteristic of my invention will be definitely indicated in the claims appended hereto.

25 The details of construction and mode of operation of a preferred embodiment of my invention will be understood by reference to the following description taken in connection with the accompanying drawings, in which:

30 Figure 1 is a perspective view of my invention embodied in an electrical measuring instrument of the curve drawing type; Fig. 35 2 is an enlarged perspective view of the details of construction of my novel mechanical movement; and Fig. 3 is a perspective view 40 of a modified construction embodying my invention.

I have illustrated my invention embodied in an electrical measuring instrument of the curve drawing type. My invention, while 45 particularly adapted for use in such an instrument, is in no sense limited thereto, and I do not, therefore, desire to be limited to the particular application of the invention shown and described herein.

50 The instrument shown in the drawings comprises two fixed coils 5 and 6. A frame 7 carries two movable coils 8 and 9 inductively and operatively related to the coils 5 and 6 respectively. The frame 7 is rigidly secured 55 to a pivotal shaft 10 having a control spring

11 of the usual type. A movable member 12 is also rigidly secured to the shaft 10. The effect of the currents flowing in the coils is to produce a repelling action between the inductively related coils, and accordingly, 60 the coils 8 and 9 will move away from the coils 5 and 6 respectively. By this movement the member 12 is turned with the shaft 10 in the arc of a circle.

A U-shaped element 13 is rigidly secured 65 to the outer end of the member 12. The element 13 is preferably constructed of resilient or spring-like material. I have employed the phrase U-shaped element throughout the specification and claims of this application 70 to indicate a hollow bowed element without regard to the depth or specific configuration of the element. The element may conveniently assume a curved or bowed shape, as illustrated in the drawings, but, obviously, 75 I do not desire to limit my invention to this particular construction, and I have accordingly employed the phrase U-shaped to cover generically all equivalent configurations.

Each end of the spring element 13 is provided with a slot 14. A cord 15, preferably of silk, having a knot 16 at each end is tautly stretched across the ends of the spring element 13 with the knots 16 engaging in the slots 14. The length of the cord 15 between 80 the knots is such that the cord is held under tension due to the resilient character of the element 13.

A link 17 is arranged for substantially reciprocatory movement and has secured 85 to each end a spring element 13 of identically the same construction and characteristics as the spring element secured to the end of the movable member 12. The ends of the spring element on the link 17 are 90 flexibly connected by a cord, as previously described. The cord secured to the spring element at one end of the link 17 is tied at substantially its middle portion to the cord secured to the spring element on the movable member 12. These cords are preferably secured together by a knot 18, as will be clearly seen by reference to Fig. 2 of the drawings. The knot is preferably located at substantially the middle portion of each 100 cord, and the spring elements are so arranged that the cords lie in substantially the same plane and form substantially right angles with each other.

The cord 15 secured to the spring mem- 110

ber at the other end of the link 17 is operatively connected to a movable member 19. The member 19 is rigidly secured to a pivoted shaft 20. An indicating member 21 is operatively secured to the shaft 20 and is arranged to sweep across a time actuated chart 22. The indicating member 21 is provided with a pen 23 for imparting a suitable record on the chart 22:

10 When current flows through the coils of the measuring instrument, the shaft 10 turns about its pivots and the movable member 12 turns through the arc of a circle. The movement of the member 12 is transmitted to the link 17 through the flexible connection formed by the coöperating spring elements and cords. The link 17 is thus given a substantially reciprocatory movement. By means of the connection between the link 17 and the member 19, this reciprocatory movement of the link produces a turning movement of the shaft 20 in its pivots, and the indicating member 21 is thereby moved in the arc of a circle across 25 the chart 22. The position of the pen point 23 on the chart will give an indication of the strength of current to be measured.

I prefer to secure the coöperating cords together by means of a knot, but it will be apparent that other connections may be employed. For example, a small disk 24 having equally spaced apertures, may be used for securing together four cords connecting the four ends of the spring elements, as illustrated in Fig. 3 of the drawings. It will be seen that in either construction a flexible connection is provided having four cords positioned in substantially the same plane and substantially 40 degrees apart.

It will thus be evident that I have produced a very simple device for producing a corresponding movement of two members whose paths of movement are in planes substantially at right angles to each other. The connection which I have provided between the movable members is flexible and permits a certain irregularity in the movement of the interconnecting mechanism. The connection is, furthermore, substantially frictionless and for this reason is particularly adapted for use in delicate instruments where the force of the turning movement is slight and friction loss must be carefully avoided.

55 A further advantage of my improved flexible mechanical movement results when it is used in electrical measuring instruments working on alternating current. At certain low frequencies an objectionable vibration is often produced in such instruments. The mechanical movement which I have provided acts as a flexible diaphragm and thus performs the functions of a shock absorber. In this manner a difficulty is 60 eliminated which has heretofore been very

much in evidence in certain types of electrical measuring instruments.

While, I have described a preferred embodiment of my invention, I do not desire to limit myself to this particular embodiment. I, therefore, aim in the appended claims to cover all modifications within the spirit of my invention which will be obvious to those skilled in the art.

What I claim as new and desire to secure by Letters Patent of the United States is:—

1. A mechanical movement comprising two movable members, an element having two arms resiliently spaced with respect to each other secured to each member, means 80 flexibly connecting the two arms of each element, and means whereby said last mentioned means are operatively connected together.

2. A mechanical movement comprising two movable members, an element having two arms resiliently spaced with respect to each other, a cord tautly stretched between the two arms of each element, and means 85 securing said cords together at substantially their middle portions.

3. A mechanical movement, comprising two movable members one of which has a path of movement in the arc of a circle, an element having two arms resiliently spaced 95 with respect to each other secured to one of said members, a cord tautly stretched between the two arms of said element, and means whereby the other movable member is operatively connected to substantially the 100 middle portion of said cord.

4. A mechanical movement comprising two movable members, a U-shaped spring element secured to each member, means flexibly connecting the ends of each spring element, and means whereby said last mentioned means are operatively connected together.

5. A mechanical movement comprising two movable members, a U-shaped spring 110 element secured to each member, a cord flexibly connecting the ends of each element, and means operatively connecting said cords to each other.

6. A mechanical movement comprising 115 two movable members, a U-shaped spring element secured to each member, a cord tautly stretched between the ends of each element, and means securing said cords together at substantially their middle portions.

7. A mechanical movement comprising two movable members; a U-shaped spring element having a slot in each end secured to each member, a cord knotted at its ends and 125 tautly stretched between the ends of each element the knots of the cord engaging in the slots of the element, and means for securing said cords together at substantially their middle portions.

8. A mechanical movement comprising two movable members, a U-shaped spring element secured to each member, a flexible connection having four cords positioned in substantially the same plane and substantially 90 degrees apart, and means for operatively securing the four cords to the four ends of the spring elements.
9. A mechanical movement comprising two movable members, a U-shaped spring element secured to each member, a cord tautly stretched between the ends of each element, said elements being so arranged that said cords are positioned in substantially the same plane and bisect each other at substantially right angles, and means securing said cords together at their point of intersection.
10. A mechanical movement comprising two movable members, a U-shaped spring element having a slot in each end secured to each member, a cord knotted at its ends and tautly stretched between the ends of each element the knots of the cord engaging in the slots of the element, said elements being so arranged that said cords are positioned in substantially the same plane and bisect each other at substantially right angles, and a knot securing said cords together at their point of intersection.
11. A mechanical movement comprising a rigid member arranged to turn through the arc of a circle, a second rigid member also arranged to turn through the arc of a circle, the planes of the paths of movement of said members being substantially at right angles to each other, and a link having a U-shaped spring element secured to each end and a cord flexibly connecting the ends of each spring element, one cord being operatively secured to the first mentioned member and the other cord being operatively secured to the second member.
12. A mechanical movement comprising a rigid member arranged to turn through the arc of a circle, a U-shaped spring element secured to said member, a cord tautly stretched across the ends of said element, a second rigid member also arranged to turn through the arc of a circle, the planes of the paths of movement of said members being substantially at right angles to each other, and a link having a U-shaped spring element secured to each end and a cord stretched tautly across the ends of each U-shaped spring element, the cord on said first mentioned member being operatively secured to one cord on said link, the other cord on said link being operatively secured to the second member.

In witness whereof, I have hereunto set my hand this 27th day of March, 1913.

ALEXANDER J. R. FIEGO.
